United States Patent Office

Des. 229,059

Patented Nov. 6, 1973

229,059

MOLDED FAN

James A. Swimmer, Highland Park, Ill., assignor to
Air King Corporation

Filed Apr. 5, 1972, Ser. No. 241,494

Term of patent 14 years

Int. Cl. D23—04

U.S. Cl. D23—165

FIG. 1

FIG. 2

FIG. 3

FIG. 4

FIG. 1 is a front perspective view of a molded fan embodying my new design;

FIG. 2 is a rear perspective view of the same;

FIG. 3 is a greatly enlarged, fragmentary, cross-sectional view taken substantially along line 3—3 of FIG. 1;

FIG. 4 is an enlarged, cross-sectional view taken substantially along line 4—4 in FIG. 1 showing the hub and one blade of the fan in cross-section.

I claim:

The ornamental design for a molded fan, as shown and described.
